WIRE ROLLING MILL

Jean Rozières, Saint-Cloud, France

Application December 3, 1946, Serial No. 713,737
In France September 17, 1946

3 Claims. (Cl. 80—55)

1

In order that metal wires may be rolled with high accuracy the rolls of wire rolling units must be arranged to face one another exactly. The usual play occurring in the bearings of the roll housings cannot be tolerated when the pass sections tend to throw the wire under treatment out of alignment as a result of lateral displacement of the rolls. To counteract said play it has been found necessary to mount the rolls on needle-shaped roller bearings, instead of ball bearings. However, the latter require a relatively large space, since it is necessary, for obtaining sufficiently deep passes, to employ rolls having as small a diameter as it is possible to construct. On the other hand, in order to obtain good synchronization of the various rolling units making up a wire rolling train, ordinary pillow-block bearings cannot be employed. However, needle-shaped roller bearings always give rise to axial thrusts due to the fact that such rollers dispose themselves obliquely as a result of both the peripheral clearance existing between them and the braking effect produced by their ends which bear against the roller race. Such thrusts are continuous (in the case of inclined or vertical shafts) and intermittent (in the case of horizontal shafts). These thrusts always tend to displace the rolls with respect to one another, an action which destroys the accuracy of the machine.

The present invention aims to permit rotation, without end play, of the rolls in a wire rolling unit in their bearings, as well as to permit vertical displacements, also without end play, of the bearings in the roll housings of the unit, by the provision of a system which takes up yieldably all the play which would influence the lateral shifting of a roll in the roll unit.

The two bearings of a roll may be mounted in a single block. Such an arrangement is advantageous in that it brings about a thorough alignment of the two needle-shaped roller bearings and tends to decrease lateral thrusts caused by said rollers, but it is not an indispensable feature of the invention.

In order that the invention may be well understood and readily carried into effect, the same will now be described with reference to the accompanying drawings which show, by way of example, two embodiments thereof and in which:

Fig. 1 is a sectional view showing the mounting of a roll in a wire rolling unit, according to the present invention; and

Fig. 2 is a fragmentary view of another mounting of such a roll.

2

The block 1 is adapted to receive the needle-shaped roller bearings 2 and 3 in cylindric members 4, 5, respectively, machined concentrically with respect to the axis of the roll 6 which has journals 7 and 8 adapted to rotate in the bearings 2 and 3.

The faces 9 and 11 of the block 1, which are parallel to each other, are adapted to slide without play between the columns 12, 13, 14 and 15 of the roll housing. The end edges, disposed at right angles to the axis of the roll 6 of the block 1, abut on one side against parallel slides 16 secured, as by bolts 17, to the columns 14 and 15.

At the other end, the end edges of the block 1 are acted upon by guides 18 each pressed at 19 against the corresponding column 12 and 13, respectively, and at 21 against the said end edges of the block 1, by springs 22, which are, for example, in the shape of Belleville washers, compressed by nuts 23.

The springs 22 are selected to withstand lateral thrusts caused by the needle-shaped rollers and pass shapes. They permit the block 1 to slide without any lateral play at right angles to the plane of the drawing. This sliding is necessary for the purpose of regulating the distance between the rolls.

The roll 6 itself is maintained without end play in the bearings as follows:

The journal 7, which is adapted to be motor-driven at 24, may rotate freely in the needle-shaped roller bearings 2.

The journal 8 may rotate freely in the needle-shaped roller bearing 3. The free end of journal 8 carries, disposed between its shoulder 25 and a cup-like member 26 which is pressed by a nut 27 screwed on the threaded end 28 of journal 8, the central race 29 of a double thrust ball bearing of which one outer race 31 is pressed, by a ring 32, towards the roll 6. The other outer race 33 of this ball bearing is strongly pressed, by a suitably shaped cap 34, acted upon by a spring composed for example of Belleville washers 35, surrounding a nipple 36 coaxial with the cap 34 and roll 6. This spring is acted upon by an adjustable plug 37 which may be screwed down or up within a cover member 38 adapted to maintain the cylindrical member 5 in place in the block 1. A cover member 38a holds members 2 and 4 in position.

The spring 35 is selected to withstand lateral thrusts due to inclinations of the needle rollers and pass sections.

In this construction, since the roll 6 has no

end play within the block 1 and the latter has no end play within the roller housing, it is clear that there is provided a system of mounting rolls of a wire rolling unit, in which the roll 6 will have absolutely no end play.

It is also clear that the same effect would be obtained if the block 1 were divided into two parts, each corresponding to one of the two roll journals, provided of course that end play is prevented by guiding the support of the thrust roller bearings in a manner similar to that used for the block 1.

However, the use of a single block carrier of bearings as shown, permits a better alignment of such bearings and decreases lateral thrusts caused by the needle-shaped rollers. The taking-up of end play of the thrust may also be effected according to the invention in the case of ordinary cylindric pillow-block bearings when they are used instead of ball bearings. Lateral displacement of the rolls in a wire rolling unit for the purpose of causing the grooves of the rolls to face one another may be effected by any suitable means (forming no part of this invention, hence not described herein) adapted to displace and shift the thrust, for example, by displacing the bearing carrying member 5 in the block 1.

In Figure 2, which represents only one of the trunnions of the roll, there is shown a mounting in which account is taken of the fact that the rolling mill has its rolls inclined at an angle of 45 degrees. Owing to this inclination, the needle bearings are subjected to an end friction which subjects their lower end to a greater braking action, which causes them to be disposed in an inclined position about the axis 40. As a result of this inclination of the needles in the roller bearing, there is an axial reaction on the axis 40, similar to that obtained by screwing in a screw, which tends to displace the axis of the rolling mill upwardly. In operation this reaction tends to urge the roll with force against the stop 41. Under these conditions, therefore, it suffices to employ a single thrust bearing, for example one having relatively deep grooves. A spring 42, which is compressed between the race of the needle roller bearing and the race 43 of the thrust bearing by a cap 44 secured within the piece 5 of the block 1 and bearing against cover member 45, merely serves to maintain, against the force of gravity, the roll applied against its abutment whenever the machine is stopped, i. e., when the thrust due to the needle rollers ceases. In other respects the structure of the embodiment of Fig. 2 is substantially like that of Fig. 1.

It will be understood that the invention is not limited to the particular details described and shown, and changes may be made therein without substantially departing from the scope of the invention which is intended to be defined in the accompanying claims, the specific description hereinabove relating merely to some operative embodiments for carrying out the spirit of the invention.

What is claimed is:

1. In a rolling mill having a frame with parallel columns and having working rolls journalled in needle roller bearings carried in sliding members in said frame, a bearing construction comprising, a block having two parallel lateral faces, said block being slidable along said faces between said columns in a direction perpendicular to the axes of said rolls, fixed guiding slides on said columns engaging one end face of said block, second guiding slides on said columns engaging

the opposite end face of said block, adjustable spring means acting on said second slides pressing the slides against said end face, bearing housings coaxially mounted in said block, said needle roller bearings being carried in said sliding members by said bearing housings and journaling the opposed necks of the working roll, a thrust bearing at one of said roller necks mounted in one of said bearing housings, said housing having an inner abutment engaging said thrust bearing, one race of said thrust bearing being fixed to said roller neck, and spring means acting on said thrust bearing to press the same against said abutment, said two spring means acting on said slides and said thrust bearing being of sufficient strength to counteract any normal lateral thrust on said working roll.

2. In a rolling mill having a frame with parallel columns and having working rolls journalled in needle roller bearings carried in sliding members in said frame, a bearing construction comprising, a block slidable with two lateral faces parallel to the axes of said rolls between corresponding faces of said columns in a direction perpendicular to said axes, fixed guiding slides on said columns perpendicular to said axes engaging one end face of said block, second guiding slides on said columns engaging the opposite end face of said block, both of said end faces being perpendicular to the axes of said rolls, adjustable spring means acting on said second slides pressing the slides against said end face, bearing housings coaxially mounted in said block, said needle roller bearings being carried in said sliding members by said bearing housings and journaling the opposed necks of the working roll, a double thrust bearing at the roll neck on the side of the mill opposite said spring slides and mounted in one of said bearing housings, said housing having an outwardly facing inner abutment, said double thrust bearing having a rotating mill race fixed to said roll neck, and two fixed outer races one of which engages said abutment in said bearing housing, a cap-shaped member covering the end face of said roll neck and engaging with its rim the other of said fixed outer races, a cover member fixed to said block and covering said cap-shaped member, an adjustable screw member mounted in said cover member, and spring means between said cap-shaped member and said screw member acting to press said first outer race against said abutment.

3. A bearing construction for a rolling mill having inclined working rolls journalled in needle roller bearings and a frame with parallel columns perpendicular to said working rolls, said bearing construction comprising a block slidable with two lateral faces between said columns in a direction perpendicular to said inclined rolls, means preventing any lateral displacement of said block in a direction perpendicular to said columns, bearing housings coaxially mounted in said block, said needle roller bearings being carried with their outer races in said bearing housings and journalling the opposed necks of the work roll, a ball thrust bearing at the upper end of said inclined working roll mounted in one of said bearing housings, said housing having an inwardly facing abutment means, said thrust bearing having two concentrical races, the inner race of which being fixed to said upper roll neck above said needle roller bearing and the outer race engaging said abutment, and a helical spring mounted about said roll neck between the outer races of said needle roller bearing and said ball

5

thrust bearing, said spring thereby pressing said thrust bearing against said abutment and being of sufficient strength to counteract the weight of the roll.
